UNITED STATES PATENT OFFICE.

HERBERT RAYNER, OF LOUISVILLE, KENTUCKY.

ELECTRIC COMBINATION LOCK.

1,420,575.

Specification of Letters Patent. Patented June 20, 1922.

Application filed July 27, 1920. Serial No. 399,369.

To all whom it may concern:

Be it known that I, HERBERT RAYNER, a citizen of the United States, residing at Louisville, in the county of Jefferson and 5 State of Kentucky, have invented new and useful Improvements in Electric Combination Locks, of which the following is a specification.

This invention has reference broadly to 10 an electric circuit maker.

The invention is primarily intended for controlling the electric circuit of the ignition systems of automobiles, and is in the nature of a permutation or tumbler lock wherein 15 the movable parts thereof must be brought to certain predetermined positions to bring contact members carried thereby in contacting engagement with other stationary contact members before a complete electric circuit 20 can be established.

A further object is to produce a permutation device in the nature of a contact maker for the electric ignition systems of an automobile, in which variously located contact 25 members are connected by circuit wires and said wires are connected to binding posts to which the main conductor wires are attached, each series of contact members being in the path of engagement by bridge members or 30 switches carried by tumblers that are mounted upon a spindle, which latter must be properly manipulated to so arrange the tumblers that the switches thereof will be brought into bridging relation with the contact members before a complete electric circuit 35 can be established.

It is a further object of the invention to produce a contact maker for controlling the electric conductors for the ignition systems 40 of automobiles in which a plurality of spaced contact members are employed and which have short conductors connecting the same in a manner to cause a circuit passing therethrough to take a zigzag path, certain 45 of the conductors being connected to binding posts to which the main conductors of the system are secured, and also in which turnable bridge switch members are employed for engaging with and completing the circuit 50 between the same and the contact member, the switch members being sustained in predetermined positions on a spindle that is provided with a knob having indicating marks thereon which must be brought next 55 to a common indicator on the outer face of the device before the tumblers are positioned

to bring the switches carried thereby in bridging position with respect to the device with which they are to engage, and also whereby a circuit cannot be completed by a 60 person not acquainted with the combination.

The foregoing objects, and others which will appear as the nature of the invention is better understood, may be accomplished by a construction, combination and operative 65 assemblage of parts such as is illustrated by the drawings.

In the drawings:

Figure 1 is a face view of the improvement. 70

Figure 2 is a side elevation thereof.

Figure 3 is a sectional view approximately on the line 3—3 of Figure 1.

Figure 4 is an enlarged sectional view approximately on the line 4—4 of Figure 3. 75

Figure 5 is a similar sectional view on the line 5—5 of Figure 3.

Figure 6 is a similar sectional view approximately on the line 6—6 of Figure 3.

Figure 7 is a plan view of one of the disks. 80

Figure 8 is a side elevation of the improvement, the casing being in section.

Figure 9 is a plan view of one of the bridge switch carrying tumblers.

Figure 10 is a sectional view approximately on the line 10—10 of Figure 9. 85

Figure 11 is an approximately central vertical longitudinal sectional view through a modification.

Figure 12 is a sectional view approximately on the line 12—12 of Figure 11. 90

Figure 13 is a longitudinal sectional view in a line with the switches.

Figure 14 is a plan view of one of the tumblers. 95

Figure 15 is a plan view of one of the disks.

In the embodiment of the improvement illustrated by the drawings I employ a face plate 1 which has secured to the inner face 100 thereof three equi-distantly spaced rods 2.

While not disclosed in the drawings, the face plate is designed to be secured to a suitable casing which encloses all of the parts that will hereinafter be described. Also the face plate 1, in the showing of the drawings is

in the nature of a flat disk, but it is to be understood that the same may be of any desired shape or form and also that while I will, in the following description refer to 110 the improvement provided with three series of contact members, and consequently three

bridging members or switches for the said series of contacts, any desired number of contacts and any desired number of switch members may be employed.

5 On the rods 2, and contacting with the face plate 1, are comparatively short sleeves 3 of insulating material, and resting on the outer ends of the sleeves is a disk 4 also of insulating material. The disk is provided
10 with a central opening 5 which is of a greater area than the central opening 6 in the face plate 1. On the rods and contacting with the inner face of the disk 4 are sleeve members 7 similar to the sleeve members 3, and resting on the said sleeves is the central insulating disk 8 of the improvement. The disk 8 is similar in construction to the disk 4. On the rods 2 and contacting with the inner face of the disk 8 are sleeves 9 similar
15 to the sleeves 3 and 7, and also on the rods and contacting with the inner ends of the sleeves 9 is the inner disk member 10 of the improvement. The disk 10 is similar to the disks 4 and 7. On the rods 2 and contacting
20 with the inner face of the disk 7 are sleeves 11 which are similar to the sleeves 3 and 7 and 9, but may be of a greater length than these sleeves. On the rods 2 and contacting with the ends of the sleeves 11 is the back
25 plate 12 of the casing. The rods at their outer ends are threaded, and are engaged by nuts 13 that contact with the back plate 12.

All of the disks, slightly inward of their central openings are provided with equidistantly spaced orifices 14 that extend transversely therethrough. Through two of these orifices on each of the disks there are passed conductor posts 15. These posts are, of course, removably sustained in the orifices, and therefore may be arranged in any pair of the orifices on each of the disks, it being important that the same shall be spaced a distance away from each other so as to be properly contacted by the bridge
40 switches which will hereinafter be described. Each of the posts is, of course, of electric conducting material and has one of its ends dished as at 16 and its other end projecting a slight distance beyond the face of the disk
45 and provided with a short conductor 17. It will be apparent that by changing the position of the conductor posts, which in reality provide the contact members, that the combination of the device may be readily
50 changed.

Passing through the central opening in both the front and back plates of the device is a spindle 18. The spindle has on its outer end a knob 19 that has its inner portion
60 flared outwardly as at 20, and the said flared portion of the knob is provided with spaced indicating marks 21. On the face plate 1 there is a single indicating mark 22.

Loose on the spindle 18, contacting with
65 the inner face of the plate 1, and partly

received in the central opening of the first disk 4 is a sleeve-like tumbler 23. This tumbler may be constructed of metal, as is the spindle, but the same has one of its sides cut away to provide a straight portion 24
70 which has secured thereon a plate of insulating material 26 against which is the body plate 26' of the bridge switch. The outer face of the body plate is also covered by a sheet of insulating material 27, and the insulating sheets as well as the body plate is secured to the straight wall or shoulder 24
75 of the tumbler in any desired or preferred manner. The body plate 26' at its ends has outstanding fingers 28 which are constructed
80 of spring material and which are sustained out of contacting engagement with the tumbler. The fingers, at their outer ends have cone-shaped contact portions 29 that are designed, when the tumbler is rotated by
85 the turning of the spindle, to be received in the dished ends of the contact posts 15 on the disk 4.

In a pocket entering from the outer face of the tumbler 23 there is pivoted, as at 30 a
90 dog 31 that is influenced by a spring 32 to project the active end thereof through the pocket 33.

On the spindle 18, and contacting with the tumbler 23 is a similarly constructed tumbler 34. This tumbler, however, is secured to the spindle by a binding screw 35. This permits of the removal of the tumbler as well as the adjustment thereof with respect to the spindle. The tumbler 34 has a bridge
95 switch similar to the bridge switch in action with the tumbler 23, the last mentioned switch including a body plate insulated from the metallic tumbler and having its ends provided with spring fingers 36 that are
100 formed at their ends with cone-shaped contact points 37. The contact ends of the fingers of the switch are designed to be received in the dished ends of the contact posts 15 on the disk 8, when the spindle turns the tumbler 34 to bring these elements into such engagement. The tumbler 34 has its face, adjacent the confronting face of the tumbler 23 provided with a notch 38 to receive
105 therein the dog 31 whereby the tumbler 23
110 may be caused to turn with the spindle and with the tumbler 34 when the spindle is manipulated. The tumbler 34, upon its opposite end has a pocket within which is received a pivoted spring pressed dog 39, similar to the dog 31, the face of the said dog
115 39 being projected by its spring through the pocket so that the same may be brought into engagement within a notch 40 on the confronting face of the outer tumbler 41. This last mentioned tumbler is loosely mounted,
120 on the spindle, and has one of its sides notched to provide a straight wall against which the body plate of the bridge is received, the said body plate being, however,
125 130

insulated from the said shoulder. The body of the switch has its ends provided with outwardly sprung fingers 42 that terminate in cup-shaped contact ends 43 which latter are 5 designed to be received in the dished ends of the contact posts 15 of the outer sleeve 11, when the spindle is properly manipulated to bring the said members to such position.

The conductor 17 from one of the contact 10 members or posts 15 on the disk 8 leads and is connected to the contact member 15 directly below the first mentioned contact member. The contact post 15 on the disk 4 directly opposite the referred to contacts on 15 the disks 8 and 10 has its conductor 17 connected to the contact post on the disk 10 directly below the first mentioned disk. On the back plate 12 are binding posts 44 and 45 respectively, and a conductor wire from the 20 binding post 44, indicated for distinction by the numeral 45', leads from the said post to the second contact member or post 15 on the disk 4. From the binding post 45 a conductor wire 46 leads to the second contact member 25 or post on the intermediate disk 8, opposite that, of course, to which the conductor 17 is attached. The power wires 47 and 48 are connected with the binding posts 44 and 45, and it will be noted that the spindle must 30 be manipulated to cause the turning of the intermediate tumbler thereon, and to cause the intermediate tumbler to turn the end tumblers so that all of the bridge switches carried by the tumblers will properly engage 35 with the respective contacts on the separate disks. When this is accomplished the current will flow through the wire 45', from the binding post 44, through the contact 15 on the first disk 4, through the bridge switch 40 connected to the outer or first tumbler 23, through the second contact post 15 on the said disk 4, through the conductor 17 to the contact post on the disk 10, across the bridge switch carried by the tumbler 34, through the 45 second contact member 15 on the disk 10, through the conductor 17 and the contact member 15 on the disk 10, across the bridge switch carried by the intermediate tumbler 34, through the second contact member on 50 the intermediate disk 8, through the conductor wire 46, binding post 45 and through the return wire 48, thus completing the circuit and allowing the same to flow through the electric ignition system of the automobile for 55 permitting the operation of the instrument. The foregoing construction refers to one embodiment of the improvement. A second embodiment is illustrated in Figures 11 to 15. The general construction is similar to 60 that previously described, that is spaced disks of insulating material are employed as is also the spindle provided with the tumblers and the contact members on the disks. It will be noted that in the modified form 65 three disks 49, 50 and 51 are employed.

Each of the disks has a contact post 52 and a switch member 53 normally out of engagement with the contact. The contacts are wired in a manner as previously described, and switches 53 are pivoted as at 54 and are 70 spring influenced as at 55. Bridge wires 56 connect the pivoted switch members on the respective disks, and these bridge members are in the path of contact with a circuit closer on each of the tumblers 57, 58 and 59. 75 The circuit closers are preferably in the nature of spring influenced members 60 in the respective disks. The intermediate disk is fixed to the spindle 62, the other disks being 80 loosely mounted on the said spindle. Between the disks are the pawls and the notches which receive the pawls therein when the disks are brought to certain positions. It should have been stated that the notches providing the pockets for the pawls have their 85 inner walls arranged at an angle so that the tumbler disks can slip or ratchet over the pawls when turned in one direction, and also that the pawl of one of the disks will cause the turning of the other disk there- 90 with when the spindle is turned in another direction. In the present instance the contact members carried by the tumblers engage with the bridge wires between the switches to influence the latter against the tension of 95 their springs to permit the said switch engaging with the contacts so that an electric circuit can be thus completed.

It is believed that the foregoing description, when taken in connection with the 100 drawings will fully set forth the simplicity of the construction and the advantages thereof. With the improvement it is practically impossible for a car to be started by a person not acquainted with the combination of 105 the lock. The device is of a simple nature, and may be manufactured and marketed at a comparatively small figure.

Having thus described the invention, what I claim is:—

1. In an electric switch, spaced insulation disks, conductor posts arranged in pairs passing through each disk and having one of their ends dished, a spindle passing through the disks, tumblers thereon, one of 115 said tumblers being received in each of the disks, spaced connected bridge switches carried by each tumbler having a cone-shaped end designed, when the tumblers are rotated by the spindle to certain positions to be received in the cupped ends of the posts, the central tumbler fixed on the spindle, and means, including spring influenced elements between the tumblers designed when brought into coengagement for latching the end 120 tumblers to the central fixed tumbler, and electric conductors connected to the posts and bridge switches.

2. An electric switch comprising spaced insulation disks, each having a circular 130

series of orifices, two conductor posts removably secured in two of the orifices of each disk, a spindle passing through the disks and bearing means for the spindle, a 5 fixed tumbler and loose tumblers on the spindle, and revoluble in the disks, certain of said tumblers having their confronting faces notched, the other tumblers having spring influenced dogs seated in pockets de- 10 signed to engage with the notches when the spindle is turned to one position, a bridge switch on each of the tumblers, but insulated therefrom designed to have wiping engagement with the conductor posts 15 on the disks against which the bridge switches contact, and electric conductors for the bridge switches and for the posts.

3. In a device for the purpose set forth, a casing, spaced disks of insulating material 20 therein, each of said disks having a series of spaced orifices therethrough, contact members received in certain of the orifices, binding posts on the casing, electric con-

ductors connected therewith, conductors between the binding posts and certain of the 25 terminals on the disks, conductors between the remaining terminals on the disks, a revoluble spindle having a graduated knob, and a dial on the outer face of the disk, fixed and loose tumblers on the spindle, 30 spring influenced dogs carried by certain of the tumblers and the other tumblers having notches to receive the dogs whereby all of the tumblers may be revolved in unison, conductor bridge members carried 35 and insulated from each of the tumblers, each of said bridge members having offset fingers terminating in contact elements designed, when the tumblers are brought to certain positions to engage with the terminals of the respective disks and to complete the electric circuit through the terminal bridge members therefore and the conductors for the terminals. 40

In testimony whereof I affix my signature. 45
HERBERT RAYNER.
